ELECTROLYTIC ALKALI CHLORINE CELL

Samuel L. Burns and Martin Chesterfield, Niagara Falls, N. Y., assignors to Hooker Electrochemical Company, Niagara Falls, N. Y., a corporation of New York

Application September 4, 1940, Serial No. 355,346

6 Claims. (Cl. 204—257)

Our invention relates more particularly to an alkali chlorine cell for production of caustic alkali, chlorine and hydrogen from alkali metal chlorides.

Our invention is a modification of the alkali chlorine cell disclosed in Patent No. 1,866,065. One object of our invention is to provide a cell having certain of the characteristics of the cell disclosed in this patent but having no concrete in its construction. Another object of our invention is to provide a cell of the general type referred to but having only one joint to be sealed against leakage.

Referring to the drawings:

Fig. 1 is a plan view of our cell, partly cut away to show the interior construction.

Fig. 2 is a side elevation of our cell, in section along line *a—a* of Fig. 1.

Fig. 3 is an end elevation of our cell, in section along the line *b—b* of Fig. 1.

Figs. 4, 5 and 6 are perspective views of a number of cathodic electrode elements, illustrating one method of constructing and assembling them.

Fig. 7 is a plan view of a modified embodiment of our invention, in section along line *d—d* of Fig. 8.

Fig. 8 is an elevation of this modification, in section along line *e—e* of Fig. 7.

Fig. 9 is a perspective view of a portion of the foraminous cathodic electrode structure, in perspective, looking upward from below.

Referring to the figures:

Our cell comprises a cathode assembly forming a liquid-tight base member and an anode assembly resting upon and making a liquid-tight joint therewith.

The cathode assembly comprises a rectangular container or tank 1, preferably of steel, housing the cathodic electrode structure. Inside the rim of tank 1, along each of its four sides, is a member 2, of angle section, the horizontal leg of the angle being welded to the rim to form a passage 3 extending all around the rim. The purpose of this passage will be discussed later. The bottom of tank 1 is reinforced by ribs 4, extending transversely of the cell, and staggered ribs 5, 6 and 7, 8, extending longitudinally of the cell. Pads 9 and web 10 complete three points of support upon which the cell may rest, upon insulators (not shown) supported from the floor.

The active surface of the cathode assembly consists of a series of thin, flat, foraminous cathodic electrode members 11, having flat, ver-

tical faces. These cathodic electrode members are adapted to alternate with the anodic electrodes, to be described later. In the preferred embodiment of the invention, they are parallel with each other and arranged in two groups or banks. The members of each bank are perpendicular to a side wall of tank 1. Between the two banks is a clearance or passage 12, to facilitate circulation of electrolyte (see Figs. 1 and 3). Between each bank of cathodic electrode members and the side wall with which the members are perpendicular is a clearance or passage 13, which communicates with passage 3. Between the bottom of tank 1 and the banks of cathodic electrode members is a clearance or passage 14, with which the open bottom edges of the clearance between these members communicate. The two banks of cathodic electrode members are joined together along their lower inner edges by a strip of foraminous metal similar to that from which the electrode members themselves are formed. Each bank of cathodic electrode members is also conductively joined to the angle member 2, to which it is adjacent, by strips of similar foraminous metal.

The form of these cathodic electrode members will be better understood from Figs. 4, 5 and 6 which illustrate one method of constructing these members. A long sheet of foraminous metal, preferably of steel wire screen, having a width slightly greater than the height of the finished electrodes, is first bent into wide corrugations separated by narrow corrugations. The wide corrugations are of a width equal to the distance which is to separate the active cathodic surfaces, between which surfaces the anodic electrodes are later to be installed, clearance being provided between the anodic and cathodic electrode surfaces for circulation of electrolyte. The narrow corrugations are of a sufficient width to provide passages between the active cathodic electrode surfaces for removal of hydrogen and liquid products resulting from the electrolysis. The edges of the screen are then peened toward each other until they meet. At one side of the sheet the edges of the wide corrugations are peened toward each other until they meet in seam 15, where the wires are butted and welded. At the other side the edges of the narrow corrugations are peened toward each other, preferably over a semi-circular mandrel, until they meet in seam 16, where the wires are likewise butted and welded. The screen is also peened outward at the roots of both the narrow and wide corrugations, as illustrated at 17, Fig.

4. Strips of wire screen are then scalloped along one edge, the other edge being left straight. A portion of such a strip is illustrated at 18, Fig. 6. Other strips are scalloped along both edges. A portion of such a strip is illustrated at 19, Fig. 5. The radii and pitch of these scallops are those of the peened roots 17. These strips are butted and welded along their scallops to roots 17 of the cathodic electrode members 11. Two banks of cathodic electrode members are thus assembled into units. The number of cathodic electrode members 11, formed and assembled in each bank depends upon the current under which the cell is intended to operate, and other practical considerations. Strips 18 are then continued around the ends of the cell as illustrated at 20 and strips 19 are carried up the ends of the cell as illustrated at 21. After the cathodic electrode members 11 and strips 18, 19, 20 and 21 have been assembled in this way, a steel supporting structure is inserted between the walls of these electrodes, behind their roots and below their lower edges. This structure is made up of members 23, 24 and 25. Members 23 are flat strips of steel of a width to slide freely into the clearances between the electrodes 11 but wide enough to support their walls against collapsing pressures. Members 24, to which members 23 are welded at their intersections, form with members 23 a rake like structure, the pitch of the teeth of the rake being exactly that which it is desired that the series of parallel cathodic electrode members should finally have. Vertical members 25, to which members 23 and 24 are welded at their intersections, space the two rake-like structures on each side of the cell at the desired distance apart and height from the bottom of the cell. Members 26, mounted upon legs 27, support the bottom edges of each bank of cathodic electrodes. Members 28 complete the supporting structure. These are horizontal flat strips welded to the lower free edge of angle member 2, and also welded to each other at the corners of the cell, so that they form a shelf extending inward from angle member 2. Strips 18 and 20 of wire screen overlap and rest upon this shelf.

Strips 18 and 20 are conductively welded to angle member 2 and members 28. The outer ends of members 23 and the lower ends of members 25 are welded to the shell of tank 1. Members 25 are also welded to the horizontal wires of the screen itself at the root of the cathodic electrode.

Cathodic electrode members 11 are covered with a permeable diaphragm as indicated by the speckled surfaces, dividing the cell into an anode compartment and a cathode compartment. This is preferably of asbestos fiber. It will be noted that the active cathode surface is formed by two or more sheets of wire screen which is corrugated in both the vertical and horizontal planes, hence has warped (e. g., quarter spherical) surfaces where the convolutions intersect. Such surfaces could not be covered by a sheet of paper. The diaphragm can therefore best be applied by the method disclosed in U. S. Patents Nos. 1,855,497 and 1,862,244 and 1,865,152. The diaphragm formed in this way will cover strips 18 and 20 and will therefore be overlapped and have its edges sealed by non-conducting coating 39.

The anode assembly comprises a rectangular main frame 30, of angle section, formed of four pieces welded at the corners, supporting a se-

ries of graphite anodic electrodes 31. The proportions and dimensions of frame 30 conform to the inner wall formed by angle member 2, with however a suitable clearance for insulation. Frame 30 rests upon insulating blocks 32 which in turn rest upon strips 18 and 20, which of course are supported by the rigid shelf formed by members 28.

Frame 30 is covered by rectangular plate 33, to which the vertical leg of its angle section is welded all around the frame, except where bus bar 34 enters through a slot in the vertical leg of the angle to make contact with the under surface of plate 33. Beneath cover 33 is a slab 35 of low melting metal or alloy, preferably lead, extending between the end members of frame 30 and retaining members 36, which are parallel to a side member of frame 30. In lead slab 35 are embedded, for a short distance at their upper ends, the graphite blades which constitute anodic electrodes 31. These blades are thin, flat, elongated plates adapted to alternate with cathodic electrode members 11, with however, sufficient clearance between to permit of circulation of the electrolyte. In the particular embodiment of our invention illustrated, these blades are arranged in groups of three, placed edge to edge, each group of blades being in parallel alignment with a series of other similar groups, the entire series forming two banks of electrodes, leaving clearance 12 open for circulation of electrolyte. The anodic electrodes thus depend from the top or cover of the cell and extend nearly to the bottoms of the cathodic electrode members, a clearance being, however, provided at the bottom for circulation of electrolyte. Each anode blade has two holes drilled through it near the end which is to be embedded in lead. Each blade is also notched where it is contiguous with the adjoining blade. The lead is introduced in a molten condition, and as it flows through the holes and notches the blades are anchored to the lead securely.

The inner surfaces of frame 30, cover 33, lead slab 35 and members 36 is protected against electrolysis by a non-conducting layer 38, preferably of bitumen or asphalt. This is likewise poured in while molten and flows through the notches between contiguous blades. When the anode assembly is in place and resting upon insulating blocks 32 the joint between it and the cathode assembly is sealed by pouring in bituminous material 39.

At a point above passage 12, preferably at the geometrical center of the cell, an exit 40 is provided for chlorine. This comprises a section of ceramic pipe 41 in an envelop 42 of steel, the bitumen of non-conducting layer 38 being allowed to fill the space between. Between the upper edges of cathodic electrode members 11 and the lower surface of non-conducting layer 38, sufficient clearance is provided for circulation of electrolyte and to permit the chlorine liberated on anodic electrodes 31 to find its way to passage 12 and thence to exit 40.

Hydrogen liberated on the cathodic side of the diaphragm finds its way beneath the top walls of the cathodic electrodes to and through passage 3 to exit 44.

The liquid products of electrolysis, together with undecomposed electrolyte, find their way through the open outer ends and bottoms of the cathodic electrodes to the cathode compartment, whence they are discharged through pipe 45, which, although connected to tank 1 near its

bottom is preferably formed with a high point slightly below the level of the upper edge of cathodic electrode members 11, so that the cathode compartment of the cell is normally nearly filled with liquid.

In order that the discharge passages from the cathodic electrodes may be more clearly visualized, a portion of the foraminous cathodic electrode structure, in perspective, looking upward from below, is shown in Fig. 9, the supporting structure being omitted for simplicity. In this figure the discharge of hydrogen and liquid products from the open outer ends and bottoms of the cathodic electrodes is clearly indicated by the arrows.

Electrolyte may be supplied to the cell in the form of a jet (not shown) directed downwardly into chlorine exit 40. The level of the electrolyte within the cell is indicated by a stem 47 attached to float 48, which floats in tube 49. The lower end of tube 49 is upturned to prevent escape of chlorine. Stem 47, float 48 and tube 49 are preferably of glass.

Bus bar 46, which is conductively connected to tank 1, together with bus bar 34, already referred to, serves to complete the electrical connections to the cell.

Figs. 7 and 8 illustrate a modification of our cell in which the shape in plan is circular. In these figures, parts that are analogous to parts illustrated in Figs. 1 to 3 are indicated by the same reference numbers, followed by the suffix *a*. Thus, the tank is 1a, the cathodic electrode members 11a, the central, peripheral and bottom clearances or passages 12a, 13a and 14a respectively, the shelf 28a, the anodic electrodes 31a, the cover 33a, the lead slab 35a, the bitumen covering 38a, the chlorine exit 40a, the ceramic dome 41a, the hydrogen exit 44a and the exit for liquid products 45a. In this case the side walls of the cathode electrode members 11a are of course radial. The particular advantage of this embodiment of our invention is that it permits the electrolyte to be introduced at the exact geometrical center of the cell, thus securing equal distribution to all the electrodes.

While we have illustrated and described one method of forming the cathodic electrodes, we do not wish to be strictly limited thereto, as other methods of forming these electrodes will suggest themselves to persons skilled in the art.

We claim as our invention:

1. In an electrolytic alkali-chlorine cell, a cathode assembly comprising an open, liquid-tight, metal tank adapted to carry the cell current and housing a foraminous, caustic alkali-resistant, metal structure, said foraminous structure comprising spaced, horizontally-aligned, cathodic electrodes extending from opposite sides of said tank perpendicularly with respect thereto and with respect to the bottom of said tank and adapted to alternate and co-operate with chlorine-resistant anodic electrodes extending downwardly from above; said foraminous structure being adapted to be covered on its anode facing surfaces with permeable, chlorine-resistant diaphragm material, each of said cathodic electrodes comprising a top wall, an inner end wall and two side walls and being open at its bottom and outer end, the spaces between adjacent cathodic electrodes being bridged at their bottoms and outer ends, the outer edges of said top walls and upper edges of the outer bridge walls being conductively joined through fitted

filler strips to the rim of said tank, the lower edges of the inner cathodic electrode end walls and inner edges of the bottom bridge walls being conductively joined to a central fitted filler member similarly joined to similar edges of opposite cathodic electrodes, joining all the cathodic electrodes into a unitary structure having discontinuous bottom and side walls paralleling the bottom and side walls of said tank with corridors

10 between into which the cathodic electrodes may freely deliver products of electrolysis through their open bottoms and ends; and means for withdrawing gaseous and liquid products of electrolysis from said corridors.

15 2. In an electrolytic alkali-chlorine cell, a cathode assembly comprising an open, liquid-tight, rectangular metal tank adapted to carry the cell current and housing a foraminous, caustic alkali-resistant, metal structure comprising two banks of thin, parallel, spaced, horizontally-aligned, cathodic electrodes extending from opposite sides of said tank perpendicularly with respect thereto and with respect to the bottom of said tank and adapted to alternate and co-operate with chlorine-resistant anodic electrodes extending downwardly from above; said foraminous structure being adapted to be covered on its anode facing surfaces with permeable, chlorine-resistant diaphragm material, each of said cathodic electrodes comprising a top wall, an inner end wall and two side walls and being open at its bottom and outer end, the spaces between adjacent cathodic electrodes being bridged at their bottoms and outer ends, the outer edges of said top walls and upper edges of the outer bridge walls being conductively joined through fitted filler strips to the rim of said tank, the lower edges of the inner cathodic electrode end walls and inner edges of the bottom bridge walls being conductively joined to a central fitted filler strip similarly joined to similar edges of the opposite bank of cathodic electrodes, joining the two banks into a unitary structure having discontinuous bottom and side walls paralleling the bottom and side walls of said tank with corridors between into which the cathodic electrodes may freely deliver products of electrolysis through their open bottoms and ends; and means for withdrawing gaseous and liquid products of electrolysis from said corridors.

3. In an electrolytic alkali-chlorine cell, a cathode assembly comprising an open, liquid-tight, rectangular metal tank adapted to carry the cell current and housing a foraminous, caustic alkali-resistant, metal structure comprising two banks of thin, parallel, spaced, horizontally-aligned, cathodic electrodes extending from opposite sides of said tank perpendicularly with respect thereto and with respect to the bottom of said tank and adapted to alternate and co-operate with chlorine-resistant anodic electrodes extending downwardly from above; said foraminous structure being adapted to be covered on its anode facing surfaces with permeable, chlorine-resistant diaphragm material, each of said cathodic electrodes comprising a top wall, an inner end wall and two side walls and being open at its bottom and outer end, the spaces between adjacent cathodic electrodes being bridged at their bottoms and outer ends, walls paralleling the end walls of said tank, with corridors between, the spaces between cathodic electrodes at the extremities of said banks and said walls paralleling the end walls of said tank being bridged at the bottoms and outer ends of said cathodic elec-

trodes, the outer edges of said top walls and upper edges of the outer bridge walls and end walls paralleling the end walls of the tank, being conductively joined through fitted filler strips to the rim of said tank, the lower edges of the inner cathodic electrode end walls and inner edges of the bottom bridge walls being conductively joined to a central fitted filler strip similarly joined to similar edges of the opposite bank of cathodic electrodes, said central fitted filler strip being likewise joined at its ends to the lower edges of said walls paralleling the end walls of the tank, joining the two banks into a complete unitary basket-like structure having discontinuous bottom and side walls paralleling the bottom and side walls of said tank with corridors between into which the cathodic electrodes may freely deliver products of electrolysis through their open bottoms and ends; and means for withdrawing gaseous and liquid products of electrolysis from said corridors.

4. In an electrolytic alkali-chlorine cell, a cathode assembly comprising an open, liquid-tight, rectangular metal tank provided with an inwardly extending shelf around its rim, said tank being adapted to carry the cell current and housing a foraminous, caustic alkali-resistant, metal structure comprising two banks of thin, parallel, spaced, horizontally-aligned, cathodic electrodes extending from opposite sides of said tank perpendicularly with respect thereto and with respect to the bottom of said tank and adapted to alternate and co-operate with chlorine-resistant anodic electrodes extending downwardly from above; said foraminous structure being adapted to be covered on its anode facing surfaces with permeable, chlorine-resistant diaphragm material, each of said cathodic electrodes comprising a top wall, an inner end wall and two side walls and being open at its bottom and outer end, the spaces between adjacent cathodic electrodes being bridged at their bottoms and outer ends, the outer edges of said top walls and upper edges of the outer bridge walls being conductively joined through fitted filler strips to the edge of said shelf, the lower edges of the inner cathodic electrode end walls and inner edges of the bottom bridge walls being conductively joined to a central fitted filler strip similarly joined to similar edges of the opposite bank of cathodic electrodes, joining the two banks into a unitary structure having discontinuous bottom and side walls paralleling the bottom and side walls of said tank with corridors between into which the cathodic electrodes may freely deliver products of electrolysis through their open bottoms and ends, and means for withdrawing gaseous and liquid products of electrolysis from said corridors.

5. In an electrolytic alkali-chlorine cell, a cathode assembly comprising an open, liquid-tight, rectangular metal tank provided with an inwardly extending flange around its rim, inner walls joined to said flange and paralleling the walls of said tank, forming therewith and with said flange a gas-tight passage extending around the rim of said tank, and an inwardly extending shelf around the lower edge of said inner paralleling wall and making a gas-tight joint therewith, said tank being adapted to carry the cell current and housing a foraminous, caustic alkali-resistant, metal structure comprising two banks of thin, parallel, spaced, horizontally-aligned,

cathodic electrodes extending from opposite sides of said tank, perpendicularly with respect thereto and with respect to the bottom of said tank and adapted to alternate and co-operate with 5 chlorine-resistant anodic electrodes extending downwardly from above; said foraminous structure being adapted to be covered on its anode facing surfaces with permeable, chlorine-resistant diaphragm material, each of said cathodic electrodes 10 comprising a top wall, an inner end wall and two side walls and being open at its bottom and outer end, the spaces between adjacent cathodic electrodes being bridged at their bottoms and outer ends, the outer edges of said top walls and upper edges of the outer bridge walls 15 being conductively joined through fitted filler strips to the edge of said shelf, the lower edges of the inner cathodic electrode end walls and inner edges of the bottom bridge walls being conductively joined to a central fitted filler strip similarly joined to similar edges of the opposite bank of cathodic electrodes, joining the two banks into a unitary structure having discontinuous bottom and side walls paralleling the bottom and side 20 walls of said tank with corridors between into which the cathodic electrodes may freely deliver products of electrolysis; and means for withdrawing liquid products of electrolysis from said corridors at a level substantially above the bottom 25 of said tank but below the level of said shelf and gaseous products of electrolysis from said gas-tight passage.

6. In an electrolytic alkali-chlorine cell, a cathode assembly comprising an open, liquid-tight, 30 rectangular metal tank adapted to carry the cell current and housing a foraminous, caustic alkali-resistant, metal structure comprising two banks of thin, parallel, spaced, horizontally-aligned, cathodic electrodes extending downwardly from above; said cathodic electrode comprising elongated sheets of foraminous metal flexed into convolutions having straight side, constituting the active faces of the cathodic electrodes, joined by fillets constituting the ends and roots of the 40 cathodic electrodes, the top and bottom edges of said sheets being peened in opposite directions to form filleted flanges continued around the ends of the cathodic electrodes at the bottom and around the roots of the cathodic electrodes at the top, the top flanges being joined to form the top walls of the cathodic electrodes, the bottom flanges being joined to bridge the spaces between adjacent cathodic electrodes, the scalloped edges thus left free along the upper outer edge of each 50 of the resulting structures being conductively joined through fitted filler strips to the rim of said tank, constituting a bank of cathodic electrodes, the scalloped edges thus left free along the lower inner edge of said resulting structure being conductively joined through a fitted filler strip to the similarly scalloped edge of the opposite bank of electrodes, joining the two banks of cathodic electrodes into a unitary structure having discontinuous bottom and side walls paralleling the bottom and side walls of said tank respectively, with corridors between into which the cathodic electrodes may freely deliver products of electrolysis through their open bottoms and ends; and means for withdrawing gaseous and liquid 60 products of electrolysis from said corridors.
